I. H. SPENCER

BLOWER

Filed Jan. 10, 1925

Ira H. Spencer, *INVENTOR*
by
Arthur B. Berlak, *ATTORNEY*

UNITED STATES PATENT OFFICE.

IRA H. SPENCER, OF WEST HARTFORD, CONNECTICUT, ASSIGNOR TO THE SPENCER TURBINE COMPANY, OF WEST HARTFORD, CONNECTICUT, A CORPORATION OF CONNECTICUT.

BLOWER.

Application filed January 10, 1925. Serial No. 1,611.

My invention relates more especially to that class of blowers that are used for supplying air to pneumatic musical instruments, and an object of the invention, among others, is the production of means whereby the sounds incident to the operation of the motor for driving the blower is transmitted to a minimum degree along the conduit for supplying air from the blower to the musical instrument; and a further object of the invention is to provide means whereby the amount of air admitted to the blower will be automatically controlled to a degree depending upon the amount supplied to the musical instrument.

One form of device embodying my invention and in the construction and use of which the objects herein set out, as well as others, may be attained, is illustrated in the accompanying drawings, in which—

Figure 1 is a view in central vertical section on a plane passing lengthwise through the shaft of my improved blower.

Figure 2 is a view in section on a plane denoted by the dotted line 2—2 of Figure 1, looking toward the left, the base pieces being omitted.

Figure 3 is an end view, looking toward the right, of the structure as seen in Figure 1, but minus the base pieces.

Figure 4 is a top view of my improved blower.

In the accompanying drawings the numeral 6 indicates the case of my improved blower that may be of any suitable material, constructed in any desired manner and arranged to rest upon a saddle composed of base pieces 7. A motor 8 is mounted on a support 9 located within an open chamber 10 in the end of the case, said chamber being separated from an inlet chamber 11 by means of a wall 12 and from a fan chamber 19 by a wall 33 having an inlet opening or eye 13 for air that is supplied to the blower.

A shaft 15 is operatively connected with the motor and fans 16—17—18 are secured to the shaft. The fans 16 rotate in the chamber 19 from which a maximum portion of the air passing in at the inlet opening 13 is forced by centrifugal action of the fan 16 through an outlet opening 20 to a pipe 21 through which the air is conducted to the point where it is to be used, as to the reser-

voir for supplying an organ. The fan 17 is located in a chamber 22 separated from the chamber 19 by a wall 34 having an eye 35 through which a minimum quantity of air is drawn from the chamber 19 by the action of the fan 17 which also causes said air to flow through an outlet opening to a pipe 24 through which the air is conducted as to an organ.

Air at different pressures is required for operating different parts of an organ and the device herein shown is, therefore, equipped with means for providing air at a low pressure by action of low pressure fans 16 in the low pressure chamber 19, as well as to provide air at a higher pressure by the action of the high pressure fans in the high pressure chamber 22.

There are preferably two of the fans 18 rotating in chambers 25—26, and while the fans 16 and 17 supply air under pressure to the organ the fans 18 are suction fans for operating suction mechanism appurtenant to the organ, these fans receiving air from an inlet pipe 27 through which the air is drawn from the organ and which is exhausted through perforations 28 in the case 6.

The arrangement thus far described is very compact and enables the inclosure within a single case of a minimum size of fans for creating different pressures of air and also for creating suction with respect to an instrument, as an organ in connection with which the blower is used, the arrangement of the outlets 21 and 24 and the inlet 27 being such as to enable the compact arrangement herein illustrated.

An important feature of my invention resides in the means for controlling the flow of air to the fans 16 and 17, this control comprising valves that are automatically closed to a degree depending upon the amount of air being consumed. More or less noise is made by the motor and when the valves are open this noise is transmitted to a greater or lesser extent through the pipes for conveying the air to the organ or similar instrument being supplied by the blower. This noise is objectionable, but when the organ is playing the noise is muffled. However, when the organ is not playing there is nothing to muffle the noise and it is, therefore, important that means shall be provided

for preventing transmission of the noise at this time.

I, therefore, provide valves 29 that are located to cover ports 30 in the wall 12.

5 These valves each have a hinge 31 located on that side of the valve opposed to the direction of flow of the air currents within the chamber 11, this flow being a swirling or circular motion given to the air by a rotation of the fans and which, flowing across the valves from the hinged edge thereof, has a tendency to close the valves. When a greater quantity of air is being consumed the pressure in the conduit is reduced where-
15 by the valves open to admit more air and thereby restore the pressure in the blower, and at the same time the musical instrument being in operation the noise transmitted through the valve openings is muffled as
20 hereinbefore referred to. When the amount of air consumed by the instrument is lessened, thereby reducing said pressure, the valves gradually close owing to the reduced pressure and also to the swirling motion that
25 is set up by the fans, this swirling and circular motion being in a direction as above described to close the valves. When no air is being consumed the pressure is reduced to a minimum and the swirling motion thus
30 becomes great enough to close the valves and thus prevent noise to an objectionable extent from being transmitted to the vicinity of the musical instrument. At this time when the flow of air to the organ is stopped and when
35 the fans are running there will be nothing but a swirling motion of the air in the chamber 19, and this swirling motion under all ordinary circumstances is sufficient to overcome the action of gravity and to close the
40 valves and maintain them closed under these conditions, altho the valves with the hinges at the lower sides thereof will open when the fans cease rotating.

In order to provide for the very compact arrangement of the fans hereinbefore referred to and which arrangement comprises an important feature of my invention, the fans are so arranged that they may be supported upon the projecting end of the motor shaft, that is, a bearing is not provided at the outer end of said shaft, the single motor bearing of the shaft being sufficient. In accomplishing this result the lower pressure fan 16 which embodies the largest construction is located next to the shaft bearing and the high pressure fan 17 which is next in size is located next to the larger and lower pressure fan. The suction fans 18 which are the smallest in construction are located at the end of the shaft 15 and these suction fans, in addition to their being the lightest by reason of their size, are formed of duralium or aluminum or other light sufficiently strong metal. It is impractical to construct the fans 16—17 of these light metals and espe-

cially of duralium, as the cost owing to their size would be excessive and these fans of the greater weight are, therefore located next to the motor.

As a further aid in decreasing the length 70 of the case the backs of the suction fans are placed facing the backs of the high and low pressure fans, and this enables a decrease to be obtained in the length of the shaft and also of the case. 75

The arrangement of the narrow suction fans at the outer end of the case enables the structure to be conveniently assembled, as it is necessary to use wrenches and other tools within these chambers for the purpose 80 of assembling the parts. This may be easily done as to the chamber 19 as such tools may be inserted through the opening 20, and the same is true of the chamber 22 as such tools may be inserted through the opening in the 85 pipe 24. Such an operation, however, is im-
possible as to the chambers 25—26, but their location at the outer end of the case enables the fans to be secured as by the use of cer-
tain tools before the plates closing the cham-
bers are secured in position, and it should be
noted in this particular that a partitioning
wall 32 is located between the suction cham-
bers and the high and lower pressure cham-
bers thus dividing the end of the case 6 90
containing the motor from the opposite end
thereof. 95

In accordance with the provisions of the patent statutes I have described the principles of operation of my invention, together 100 with the device which I now consider to represent the best embodiment thereof; but I desire to have it understood that the device shown is only illustrative, and that the in-
vention may be carried out by other means 105 and applied to uses other than those above set out.

I claim—

1. A blower comprising a case substan-
tially round in cross section, a shaft extend-
ing within the case with its outer end unsup-
ported, a bearing for the end of said
shaft opposite said unsupported end, means
for driving said shaft, and a series of fans
secured to said shaft within the case, said
fans increasing in weight from the outer
unsupported end of the shaft toward said
bearing. 115

2. A blower comprising a case substan-
tially round in cross section, a shaft extend-
ing into said case with its outer end unsup-
ported, a bearing for the end of said shaft
opposite said unsupported end, and a series
of fans secured to said shaft within the case
and increasing in size from the free unsup-
ported end of the shaft toward said bearing. 125

3. A blower comprising a case substan-
tially round in cross section and having a
series of chambers including a low pressure 130

chamber, a high pressure chamber and chambers arranged in the order named, a shaft extending through said chambers and having its outer end unsupported, a bearing for the opposite end of the shaft, means for driving said shaft, and a lower pressure fan, a high pressure fan and other fans located in the said chambers in the order named.

4. A blower comprising a case substantially round in cross section and having a chamber, a second adjacent and communicating chamber of less width than the first chamber, a chamber adjacent to said second chamber and of less width than said second chamber, a shaft projecting through said chambers, fans having relative widths compared with said chambers and located therein, the end of said shaft farthest away from the widest chamber being unsupported, a bearing for the opposite end of said shaft, and means for driving said shaft.

5. A blower comprising a case substantially round in cross section and having a chamber, a second adjacent and communicating chamber of less width than the first chamber, a chamber adjacent to said second chamber and of less width than said second chamber, and divided therefrom, a shaft extending through said chambers and having its end farthest from the widest chamber unsupported, a fan located in each of the first two named chambers and of widths compared with the widths of said chambers and secured to said shaft, a fan located in the last named chamber and with its back facing the back of the fan in the adjoining chamber and secured to said shaft, and means for driving said shaft.

6. A blower comprising a case having a wall therein, a plurality of ports opening through said wall on diametrically opposite sides of the center thereof, a valve for each of said ports, means for closing all of said valves by movement of a current of fluid in a circular direction, and means within said

case for creating a current of fluid flowing in a circular direction.

7. A blower comprising a case having a wall therein, ports located on opposite sides of the center of said wall and opening therethrough, a valve for each of said ports, means for closing all of said valves by movement of a current of fluid in a circular direction, and means within said case for creating a current of fluid flowing in a circular direction.

8. A blower comprising a case having a wall therein with a plurality of ports opening through said wall on diametrically opposite sides of the center thereof, a valve for each of said ports, said valves being mounted on hinges, means for closing all of said valves by movement of a current of air in a circular direction, and means located within the case for creating a current of fluid flowing in a circular direction.

9. A blower comprising a case having a wall therein with a plurality of ports arranged on a circular line and on diametrically opposite sides of the center thereof, valves mounted on hinges to open and close said ports, the hinge for each valve being located on that side of the port opposed to movement of a current of air along said circular path, and means located in said case for creating movement of air in a circular path.

10. A blower comprising a case having a wall therein with a plurality of ports opening through said wall on diametrically opposite sides of the center thereof, a valve for each of said ports, said valves being mounted on hinges and all of the valves extending from said hinges in the same direction in a circular path, whereby said valves are all closed by the movement of a current of air in a circular direction, and means located within the case for creating a current of fluid flowing in a circular direction.

IRA H. SPENCER.
